HENRY LEMAÎTRE AUGER, OF MONTREAL, QUEBEC, CANADA.

DITCHING-MACHINE.

1,184,913.

Specification of Letters Patent. Patented May 30, 1916.

Application filed May 1, 1914. Serial No. 835,633.

To all whom it may concern:

Be it known that I, HENRY LEMAÎTRE AUGER, a subject of the King of Great Britain, and resident of 384 Ontario street, 5 in the city of Montreal, in the Province of Quebec, in the Dominion of Canada, have invented certain new and useful Improvements in Ditching-Machines; and I do hereby declare that the following is a full, clear, 10 and exact description of the same.

The invention relates to a ditching machine and the object is to devise a machine of this character simple in construction, easily operable, efficient and durable.

15 In the machine according to the invention a plowing shoe is arranged at the front end of a trough shaped guide along which the earth is conducted to a vertically arranged spiral lift conveyer which deposits 20 the earth onto a surrounding table from whence it is scraped through side openings in the table and dumped on opposite sides of the machine to form a bank on each side of the ditch.

25 The preferred form of the invention is shown in the accompanying drawings in which—

Figure 1 is a vertical section through the machine and Fig. 2 a plan view. Fig. 3 is 30 a cross sectional view through the lower part of the screw on lines A—B in Fig. 1.

Referring to the drawings the numeral 1 indicates the plowing shoe preferably V-shaped and secured to or forming part of 35 the front end of a trough shaped upwardly inclined guide 2 closed at its rear end which forms a receiver and which together with its upward tubular extension 3, serves as a conveyer tube in which is disposed the vertical 40 spiral lift conveyer 4.

The conveyer 4 extends for a distance out of the tube 3 and is provided with opposite stub shafts 5 and 6 the latter being journaled in and extending through the bottom of the 45 guide 2.

7 indicates a trough-shaped circular table, concentric with the tube 3 and supported from the upper end thereof and having the opposite outlets 8 and 9 at the sides. The 50 earth carried up by the rotating conveyer 4 from the receiver end of the trough 2 falls out of the top open end of the tube 3, onto the table 7 and is scraped from the trough thereof toward the outlets 8 and 9 by 55 scrapers 10 (say four in number) shaped to fit the trough of the table and supported by

arms 11 from the stub shaft 5 to rotate with the conveyer 4. Rollers 12 carried by the scrapers 10 preferably engage the outer edge of the table to secure easy running, and the earth which falls through the outlets 8 and 9 forms a bank on each side of the ditch cut by the shoe 1 in the forward movement of the machine.

The rear end of the machine is supported 60 on wheels 13 rigid with an axle 14 journaled in brackets 15 from the under side of the trough 2, the said axle having a bevel gear 16 fixedly mounted thereon and engaging a bevel gear 16^a rigidly mounted on the lower 65 end of the stub shaft 6 whereby rotation is imparted to the conveyer 4 from the rolling of the wheels 13 in contact with the ground.

The front end of the machine is supported 70 on a regulating roller 17 rotatably mounted at the lower end of a vertical arm 18 which is adjustable longitudinally in a sleeve 19 supported by the draft pole 20, the latter being connected at its rear end 21 to the trough 2. A detachable pin 22 engages holes 75 in the sleeve 19 and arm 18 to fix the height of the roller 17. It will thus be seen that the depth of cut made by the shoe 1 will be according to the height of the said roller 17 80 which rolls on the ground in front of said 85 shoe.

A pair of handles 23 extend rigidly from the rear end of the trough 2 which may be held by the operator for guiding purposes.

24 is a small roller rotatably mounted in a 90 bracket 25 which is slidably mounted on a pair of parallel guide rods 26, secured to the underside of the trough 2. These rods extend through longitudinal bores in the bracket, as shown in Fig. 1. To the bracket 95 25 is connected a flexible rod 27 leading to a point on one of the handles within reach of the operator. The purpose of this roller is to support the front end of the machine when not in use and it will be seen that when 100 the bracket 25 is pushed to the forward end, the shoe 1 and roller 17 are lifted out of contact with the ground and when the said bracket is drawn along the guideways 26 by pulling on the rod 27, the said roller 24 will 105 be lifted up along the inclined trough to a non-operative position.

Colters or knives 28, 29 and 30 are preferably supported at the front end of the trough 2 adjacent to the shoe in order to 110 cut the sod, the former being supported by the draft pole in a position adjacent to the

point of the shoe to cut the sod centrally, and the latter being supported at the rear end of the shoe, that is to say, at the front edge of the sides of the trough 2 so as to 5 cut the sod the right width to enter the trough 2 without jamming. Further, there is a pair of knives 31 supported vertically by the lower end of the conveyer 4 to slice the sods into smaller pieces as they enter the 10 rear end of the trough 2.

Knives 31, as shown in Fig. 1 are arranged parallel with the axis and the outer edge. They extend from the lower to the upper wall of the first or bottom spiral. One 15 only of the two knives is shown in Fig. 1. The other is identically the same and diametrically opposite—therefore, not visible.

It is thought that the operation of the invention will be clearly understood by the 20 foregoing description, but it must be understood that such modifications as found desirable may be made in the construction of the machine, so long as they come within the scope of the following claims for novelty.

25 What I claim is:—

1. In a ditching machine, an upwardly inclined trough shaped guide having a digging shoe at the front end and closed at its rear end, draft means extending forwardly from

said guide, colters suitably arranged to longitudinally cut the sods entering said guide, a depth regulating roller adjustably supported from said draft means in front of said shoe, a pair of rear wheels supporting the rear end of said guide, a spiral conveyer 30 vertically arranged in said rear end and adapted to lift the earth therefrom, cutters on said conveyer adapted to cut the sods transversely, means for rotating said conveyer from said rear wheels, and means for 35 guiding the earth lifted by said conveyer away from the machine.

2. In a ditching machine, an upwardly inclined trough shaped guide having a digging shoe at its front end and closed at its rear 40 end, draft means therefor, a spiral conveyer vertically arranged in said rear end, vertically extending cutting knives carried by the lower part of said conveyer and arranged between the axis of the conveyer and its edge, 45 and means for rotating said conveyer.

Signed at Montreal, Quebec, Canada, this 7th day of January, 1914.

HENRY LEMAÎTRE AUGER.
